(57) **CLAIM**

The ornamental design for a packaging container, as shown and described.

DESCRIPTION

1. Packaging container

1.1 : Perspective

1.2 : Open State Perspective view

1.3 : Front

1.4 : Back

1.5 : Top

1.6 : Bottom

1.7 : Right Side view

1.8 : Sectional view along line A-A

The broken lines in the drawings illustrate portions of the packaging container and form no part of the claimed design; the reproduction 1.8 is a reduced-scale cross-sectional view along the line A-A in the reproduction 1.2; the left side view is omitted because it is a mirror image of the right side view.
